HARRY G. NORWOOD, OF BALTIMORE, MARYLAND, ASSIGNEE TO A. D. T. LIBBY, OF NEWARK, NEW JERSEY.

RUBBER HEEL.

Application filed February 10, 1927. Serial No. 187,347.

This invention relates to a resilient heel, for use on boots, shoes and the like.

In the past many designs of resilient or rubber heels have been proposed, but my present invention is directed more to an entirely new design, rather than to improvements on the prior art designs, and the advantages of my present invention may be briefly set forth as follows.

10 The resilient heel disclosed herein is directed to one in which a combination of arches have bases which coact to sustain the adjacent arch or arches, whereby much greater resilience is obtained than in other heels which have been proposed.

15 The construction is such that the amount of material used in making the heel is materially reduced, in some cases as much as half. Another object of my invention is to provide a construction by which the outer cavities produced by the arches act to prevent slipping or skidding to a high degree and due to the arch construction, greater resilience is obtained, and the wear on the heel is reduced to a minimum.

20 Referring to the drawing, Figure 1 is a plan view of the bottom of the heel, while Figure 2 is a longitudinal section through the heel.

25 The heel comprises a rim portion 1, having the edge 2 adapted to fit closely against the heel lift of the boot or shoe. The heel is provided with the usual holes 3 for nailing the heel to the shoe lift. 4 is the usual metal washer which acts to limit the driving of the nail onto the lift. Preferably around the hole 3 is a series of slight corrugations 8 which add to the appearance of the heel.

30 Between the confines of the rim 1, the heel is constructed of a plurality of arches, two being illustrated, the central arch 5 is surrounded by an annular arch 6, the arches having a common abutment 7, which preferably engages the lift of the shoe, when the heel is put in position thereon.

45 It will be noted that the arches 5 and 6 are very much thinner than the rim 1, and due to this thinness of the wall and the arch construction, the amount of rubber required in the heel is materially reduced. By making the arches 5 and 6 relatively thin, greater resilience is obtained, yet it will be seen from a

study of the drawing that in use when pressure is applied to either of the arches, the strains applied thereto are conveyed through 55 the common abutment 7 to the other arch or arches so that the equilibrium of the arches is maintained and greater resilience results. The annular cavity 9 formed on the outer surface of the heel between the arches 5 and 6 60 reduces a tendency to slip or skid to a minimum.

While I have shown one form of arranging the arches it is to be understood that I do not wish to be limited unduly in the interpretation of the appended claims.

Having thus described my invention, what I claim is:

1. In a flexible heel having a rim portion to fit on the heel lift, means for increasing the 70 resilience of the heel comprising a central arch and an annular arch between the rim and the central arch, said central arch being proportioned so as to have somewhat more resilience than the outer arch.

2. A resilient heel having a rim portion to fit on the heel lift and a plurality of arched portions concentrically arranged and which coact to transmit the applied pressures from one arch to the other.

3. A resilient heel having a rim portion to fit on the heel lift, a central arch and an annular arch between the central arch and the rim, said central arch being of considerable length and breadth relative to said annular arch.

4. A resilient heel having a rim portion to fit on the heel lift, and a plurality of arched portions concentrically arranged and having abutments on the heel lift.

5. A resilient heel having a rim portion to fit on the heel lift, a central arch and an annular arch between the rim and the central arch, said arches having a thickness materially less than the thickness of the rim portion.

6. A resilient heel having a rim portion to fit on the heel lift, a central arch and an annular arch between the rim and the central arch, said central arch having a common abutment with the annular arch.

7. In a flexible heel having a rim to fit the 100 heel lift, means for securing great resilience, and non-skidding characteristics, comprising a plurality of spaced concentric arches forming outer surface suction areas therebetween,

said arches having a thickness of section materially less than the rim.

8. In a flexible heel having a rim to fit the heel lift, means for securing great resilience, and non-skidding characteristics, and minimum of weight comprising, a central arched portion and an annular arched portion hav-

ing a common abutment with the central arch against the heel lift, the outer convex surface of said arches forming an annular suction 10 ring while said arches are of much less thickness than the rim.

In testimony whereof, I affix my signature
HARRY G. NORWOOD.
